(57) **CLAIM**

We claim the ornamental design for a droplet ejection device, substantially as shown and described.

DESCRIPTION

FIG. 1 is a front elevation view of a droplet ejection device showing our new design;

FIG. 2 is a front elevation thereof, with the droplet ejection device in an alternate position;

FIG. 3 is a top plan view thereof;

FIG. 4 is a side elevation view thereof;

FIG. 5 is a front, bottom-right perspective view thereof; and, FIG. 6 is a front, top-right perspective view thereof.

The broken lines shown in the drawings represent boundaries to the claimed design with the lines themselves and all within forming no part of thereof.
